UNITED STATES PATENT OFFICE.

BERNARD D. WILLIS, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,345,054.

Specification of Letters Patent. Patented June 29, 1920.

Application filed April 8, 1914, Serial No. 830,399. Renewed August 1, 1918. Serial No. 247,862.

To all whom it may concern:

Be it known that I, BERNARD D. WILLIS, a citizen of the United States of America, and resident of Chicago, Cook county, Illinois, have invented certain new and useful improvements in Automatic Telephone Systems, of which the following is a specification.

My invention relates to improvements in automatic telephone systems and has for its object the provision of improved means for controlling the operation of automatic switches, and more particularly to improved means for controlling these switches over a circuit including two sides of a line in series.

The object of my invention is to provide means for controlling automatic switches which include a plurality of operating magnets, together with means for successively switching the operating magnets into operative position, which operating or motor magnets are controlled by impulses of one character, while the switching operations are controlled by impulses of a different character.

In the accompanying drawings I have illustrated my invention in connection with automatic selector and connector switches of well-known types, and while I have shown but a single selector switch for extending connection to the connector, it will, of course, be understood that second selectors controlled in a manner similar to that of the first selector could be inserted between the first selector and the connector.

In the drawings Figures 1 and 2 taken together show a complete circuit connection between a calling substation A and a called substation A' in a system embodying the principles of my invention.

Fig. 3 is a view showing a portion of the impulse-transmitting mechanism.

Referring to Fig. 1, there is shown a subscriber's substation A, the line conductors of which terminate in the individual or line switch C. This line switch is one of a group of similar line switches, the plungers (not shown) of which engage a shaft and are controlled by the operation of the master switch D in such a manner that they are, when in normal position, held directly in front of the terminals of an idle trunk line leading to a selector E. The selector E is the means for extending the connection to

the connector switch H (Fig. 2), which completes the connection to the called subscriber's line A'.

The subscriber's substation A may be of any suitable or approved type and comprises the usual receiver 2, transmitter 3, ringer 4 and condenser 5. It is also provided with a suitable impulse-sending device similar to that shown and described in British Patent No. 29,654 of 1910, issued to S. G. S. Dicker, except that two extra impulse springs are added, together with means for controlling the same. Referring to the substation A, the impulse-sending device comprises a pair of impulse springs 6 and 7, a pair of auxiliary impulse springs 9 and 10 and an impulse wheel 8, which latter is controlled through the medium of a finger hole dial (not shown) in such a manner that the impulse springs 6 and 7 may be momentarily separated a number of times corresponding to the digit called to transmit a plurality of impulses over the line, and which impulses are then followed by one or more rapid impulses transmitted by the impulse springs 9 and 10. Referring to Fig. 3, a pawl 12 is secured to the rotatable portion 11 of the dial, one end of which pawl is held in normal position against the pin 13 by a spring 14. When the dial is rotated in a counter-clockwise direction, the pawl 12 strikes the spring 10 in such a manner as to tilt the said pawl downward, thus allowing it to pass the spring 10 without causing it to break contact with the spring 9; but when the dial is released and the rotatable portion 11 rotates back to normal, one or more impulses are transmitted over the line conductors by means of the impulse springs 6 and 7; then, just before the dial has returned to normal position, the pawl 12 engages the spring 10 (as shown in Fig. 3) and flexes it to the right until the pawl 12 has passed beyond the said spring.

The instant the pawl 12 releases the spring 10, it flexes to the left and separates from the spring 9, sending one or more quick or high frequency impulses. It is, of course, understood that any suitable dial or call-sending device may be used and that I do not wish to limit myself to the exact construction shown herein.

The subscriber's individual switch C is of the general type of subscriber's switch shown in British patent to R. W. James No. 110

26,301 of 1906, being, however, of the particular type shown in British patent to T. G. Martin No. 1419 of 1910. This line switch comprises, among other details, a 5 plunger (not shown) attached to the end of a so-called plunger arm 15 which is controlled by the magnet 17. The magnet 17 comprises four windings, namely, a pull-down winding 18, a cut-off or holding winding 19, a line winding 21 and an auxiliary winding 20. The core of the magnet 17 is so constructed that the magnetic circuit of the windings 18 and 19 is separate from that of the windings 20 and 21. The winding 18 10 operates both the plunger arm 15 and the cut-off armature 16, while the winding 19 is only strong enough to operate the cut-off armature 16 and to hold the plunger arm 15 in its operated position. When the plunger 15 arm 15 is operated, the plunger is forced into a bank of contact springs, forcing the springs 23, 24, 25 and 26 into engagement with the springs 27, 28, 29 and 30, respectively. Although only one set of springs 25 (23-30) is shown, each line switch is provided with a plurality of such sets, each set forming the terminal of a trunk line leading to a selector switch E. Each trunk line is connected in multiple with the corresponding springs of all the line switches of the group which is controlled by the master switch D. The switch C is controlled by the subscriber through the medium of the line relay 21, as will be hereinafter more fully 30 explained.

The master switch D is of the same general type as that disclosed in British Patent No. 26,301 of 1906, referred to above, being, however, of the particular type disclosed in 40 said British Patent No. 1419 of 1910. The function of the master switch, as is well known, is to maintain the plungers of all the idle line switches in position to engage the terminal of an idle trunk line.

45 The first selector switch E is of the general type of selector switch disclosed in United States Letters Patent No. 815,321, granted March 13, 1906, to Keith, Erickson and Erickson, except that the so-called side switch is omitted and the circuits are modified to adapt the switch to operate in a system in which it is controlled by impulses delivered over the two sides of the line in series. Among other details, the selector E 50 comprises a bank of contacts arranged in horizontal rows or levels, which contacts are adapted to be engaged by a set of wipers 31, 32 and 33 carried upon a shaft (not shown) which has a vertical movement controlled by the vertical magnet 34 and a rotary movement controlled by the rotary magnet 35. The operations of various parts of the switch are controlled through the medium of the double-wound line relay 36. Means 55 for permitting the switch to be restored to

normal position is provided in the release magnet 37, which, upon energizing, withdraws the retaining pawls from the shaft in the well-known manner. Springs 38 and 39 are also provided, which springs close only 70 when the switch shaft has been raised one or more steps from its lowest position. The circuit of the release magnet 37 is controlled by the relay 40, which relay is a slow acting relay, *i. e.*, it is slow to energize when 75 its circuit has been completed. The said relay will not respond to ordinary impulses of current, but requires a steady flow of current to operatively energize. When the line relay 36 energizes, it closes the circuit of the 80 relay 62, which is connected in series with the relay 63. This latter relay, however, is normally short-circuited by the springs 41 and 42 of the line relay 36. The spring 41 is so adjusted and constructed as to follow the 85 spring 42 when the relay 36 is energized. Should one or more impulses of ordinary duration be transmitted through the line relay 36, the springs 41 and 42 will operate in unison and remain in contact, but should one 90 or more very rapid impulses be transmitted through the line relay by means of the impulse springs 9 and 10, the springs 41 and 42 will be separated for an instant due to the fact that the spring 41 is unable to follow the rapid vibrations of the spring 42. The relay 62 also controls the circuit of a relay 88, and a switching relay 86 is provided for cutting the connection through to the wipers 31, 32 and 33. The construction and operation of the switch will be hereinafter more fully explained in connection with the description of the manner in which a connection is established between a calling and a called line. 100

The connector switch H (Fig. 2) is of the same general type of connector switch as disclosed in United States Letters Patent No. 815,176, granted March 13, 1906, to Keith, Erickson and Erickson, the circuits, 110 however, being modified to adapt the switch to operate in a system in which the central office apparatus is controlled by impulses delivered over the two sides of the line in series. Like the selector, the connector is 115 provided with a shaft (not shown) carrying the wipers 45, 46 and 47, which shaft is controlled by the vertical magnet 48 and the rotary magnet 49 which are in turn controlled by the line relay 52. The usual side 120 switch comprising the wiper 50 is controlled by the private magnet 54 in the usual well-known manner. The magnet 51 is the usual release magnet. The line relay 52 is connected with the line through the reversing 125 springs of the so-called back-bridge relay 53, through the windings of which latter relay the called line is provided with talking current. The springs 55 and 56 controlled by the line relay 52 operate in the 130

same manner as hereinbefore described for the springs 41 and 42 of the selector E. The relay 99 is similar to the relay 40 of the selector E in that it is slow acting—that is, 5 slow to operatively energize and attract its armature. Ringing current is applied to the called line from the ringing generator R through the medium of the ringing relay 112 and the interrupter 117.

10 For the purpose of supplying battery current for operating the apparatus at the central exchange and for talking purposes, there is shown the battery B having one terminal grounded at G. At Q there is 15 shown a busy signaling machine which provides a busy signal, said busy signal being applied to the calling line through the medium of the busy relay 60 in case the called line is in use.

20 The substation shown at A' and the line switch C' are similar in all respects to the substation A and the line switch C.

Having given a general description of the apparatus, in order to give a clearer understanding of the operation of the system, it 25 will now be described in detail how the calling subscriber at substation A may obtain connection with the subscriber at the called substation A'. We will assume that 30 the number of the called substation is 220.

Upon the removal of the receiver at the substation A a circuit is closed through the line winding 21 of the individual switch C, thereby attracting the line armature 22. 35 The armature 22, upon being attracted, closes a circuit through the pull-down coil 18 in series with the auxiliary winding 20. The pull-down coil, upon energizing, attracts the plunger arm 15 to force the 40 plunger into the bank of springs 23 to 30, inclusive. It also operates the cut-off armature 16, thereby disconnecting the line winding 21 from the line. The armature 22 does not fall back immediately, however, owing 45 to the fact that the winding 20 is still in series with the pull-down winding 18. Upon the plunger arm 15 being attracted, the springs 61 are brought into engagement to short-circuit the auxiliary winding 20, 50 making the same slightly slow acting. The armature 22 being slow to fall back allows sufficient time for a holding circuit to be closed in the switch ahead for the cut-off or holding winding 19. The engagement 55 of the springs 23 and 26 with the springs 27 and 30, respectively, extends the subscriber's line to the line relay 36 of the selector switch E. The line relay 36 of the selector switch E is thereupon energized, closing a circuit 60 through the relay 62. The circuit extends from ground G' through the springs 43, 42 and 41, springs 64 and 72 of relay 63 through the said relay 62 to the battery lead 100, thence through battery B to ground 65 G. The relay 62, upon energizing, closes

the above-mentioned holding circuit through the cut-off winding 19 of the line switch C. This circuit extends from ground G³ through the contact of springs 67, 66 and 65, springs 70 and 69, bank springs 28 and 24 70 and the said holding winding 19 to the battery lead 100. The winding 19, upon energizing, holds the armature 16 and the plunger arm 15 in their operated positions after the circuit of the pull-in winding is 75 broken by the falling back of the line armature 22. A guarding ground potential is supplied to the connector private bank contacts of the calling line as soon as the relay 62 is energized. This circuit extends over 80 the circuit just traced to the bank spring 24, thence over the conductor 71 to said private bank contact. A further result of the energization of the relay 62 is to close a locking circuit for itself and to close a 85 circuit through the relay 88. The locking circuit for the relay 62 extends from ground G³ through the contact of springs 67 and 66, springs 73, springs 42 and 41, springs 64 and 72 and the said relay 62 to the battery lead 100. The energizing circuit for the relay 88 extends from ground G³ through the contact of springs 74 and 75 and the relay 88 to the battery lead 100. The relay 88, upon energizing, closes a locking circuit 90 for itself after springs 39 are closed, extending from ground upon the release trunk 77, springs 78, off-normal springs 39, springs 80 and 81 and through the said relay 88 to the battery lead 100. The apparatus is now 100 in readiness to receive impulses for the first digit.

The calling subscriber now operates his calling device for the first digit 2 of the called number, whereby the substation impulse springs 6 and 7 are separated twice, followed by one or more high speed impulses transmitted by the impulse springs 9 and 10. The line relay 36, responding to the two 105 impulses sent by the impulse springs 6 and 7, deenergizes twice, which operation transmits two impulses of current through the vertical magnet 34. The circuit for these impulses extends from ground G⁴ through the contact of springs 83, springs 84, springs 110 85 and the said vertical magnet 34 to the battery lead 100. It will be seen that the relay 40 receives impulses at the same time, but it is not operated, as it takes a steady 115 flow of current to operatively energize the said relay. The vertical magnet, receiving the two impulses over this circuit, operates to raise its switch shaft and wipers two steps opposite the second row or level of bank contacts. The high speed impulses which follow the two impulses just transmitted by the impulse springs 6 and 7 cause the armature of the line relay to vibrate very rapidly. 120 As hereinbefore stated, this causes the springs 41 and 42 to be separated for an in- 125 130

stant, which causes the relay 63 to be operated. This circuit extends from ground G^3 through the contact of springs 67 and 66, springs 73, relay 63 and the relay 62 to the 5 battery lead 100. The relay 63, upon energizing, opens the shunt around itself at the springs 72 and 64, thus preventing it from again becoming shunted when the springs 41 and 42 come to rest. A further result 10 due to the energization of the relay 63 is to close a locking circuit for itself, short-circuit the relay 62 and place a new holding ground upon the trunk-release conductor 77. The said locking circuit for the 15 relay 63 extends from ground G' through the contact of springs 43 and 42, relay 63 and the springs 72 and 71 to the battery lead 100. The short-circuiting of the relay 62 causes the same to deenergize, thereby 20 closing a circuit through the rotary magnet 35. This circuit extends from ground G^5 through the contact of springs 68 and 69, springs 78, off-normal springs 39, springs 80 and 81, springs 75 and 76, springs 79 and 25 the said rotary magnet 35 to the battery lead 100. The rotary magnet, upon energizing, rotates the wipers one step, and by opening the springs 79 and 78 disconnects ground G^5 from itself and from the relay 88. 30 If the first trunk line of the second level is idle, the relay 88 deenergizes immediately, but if this trunk line is busy, the private wiper 32 finds the contact with which it engages provided with a guarding ground potential 35 which is transmitted to the relay 88 through the springs 80 and 81, thereby preventing it from deenergizing. The rotary magnet, however, deenergizes when the springs 79 disengage, regardless of whether 40 the relay 88 remains energized or not. If the relay 88 remains energized, the circuit of the rotary magnet will be again closed as soon as the armature drops back far enough to close the springs 79. The rotary 45 magnet will therefore operate in the manner of a buzzer to advance the wipers step by step over the contacts until the non-grounded contact of an idle trunk line is reached by the wiper 32, whereupon the relay 88 deenergizes. The relay 88, upon deenergizing, whether after one or several operations of the rotary magnet, permanently breaks the circuit of the magnet 35 and closes the circuit of the switching relay 86. The circuit through said relay extends 50 from ground G^5 through the contact of springs 68 and 69, springs 78, off-normal springs 39, springs 80 and 82 and the said relay 86 to the battery lead 100. The relay 86, upon energizing, extends the calling line through the wipers 31 and 33 to the line relay 52 of the connector H and disconnects the line relay 36 from the said calling line. The line relay 52, upon energizing, closes a 55 circuit through the relay 87. This circuit

extends from ground G^6 through the contact of springs 57, 56 and 55, springs 89 and the lower winding of the relay 87 to battery B. The relay 87, upon energizing, closes a holding circuit for the relay 86 70 of the selector E and the holding winding 19 of the line switch C. The said circuit for the relay 86 extends from ground G^7 through the contact of springs 103 and 104, springs 93 and 94, conductor 91, wiper 32, 75 springs 80 and 82 and the said relay 86 to the battery lead 100. The holding circuit for the holding winding 19 extends over the circuit just traced to the wiper 32, thence through the off-normal springs 39, springs 80 78, bank springs 28 and 24 and the said winding to the battery lead 100. The adjustment of the relays 88 and 63 is such that the relay 87 of the connector H will be energized and provide a holding ground for the 85 trunk-release conductor 91 before the relay 63 deenergizes. A further result of the energization of the relay 87 is to close a locking circuit for itself and for the private magnet 54 and to also prepare a circuit for the vertical magnet 48 by the closure of the springs 95. The said circuit extends from ground G^7 through the contact of springs 104 and 103, and the springs 94, 93 and 96. Here the circuit divides, one branch extending through 95 the upper winding of the relay 87 to battery B, and the other circuit extending through the contact of springs 97 and the private magnet 54 to battery B. The apparatus is now in readiness for the operation of the 100 dial at the calling substation for the second digit 2.

The calling subscriber now operates his calling device for the second digit 2 of the called number, whereby the substation impulse springs 6 and 7 are separated twice, followed by one or more high speed impulses transmitted by the impulse springs 9 and 10. The line relay 52, responding to the two impulses sent by the impulse springs 110 6 and 7, is deenergized twice, thereby sending two impulses through the vertical magnet 48. This circuit extends from ground G^6 through the springs 58, springs 95, vertical magnet 48 and the side switch wiper 115 50 (in first position) to battery B. The relay 99 also receives impulses of current at this time, but it is not operated, as this relay does not respond to the impulses of current. The vertical magnet being thus operated steps the switch shaft and wipers up two steps opposite the second row or level of bank contacts. The high speed impulses that follow cause the armature of the line relay 52 to vibrate very rapidly, which operation causes the springs 55 and 56 to separate for an instant in the manner heretofore described, which operation allows the relay 101 to energize. The circuit for this relay extends from ground G^6 through the 120 115 125 130

contact of springs 57 and 56, relay 101 and the lower winding of the relay 87 to battery B. The relay 101, upon energizing, opens the shunt from around itself at the springs 89 and opens the circuit of the private magnet 54 at the springs 97. The private magnet 54, upon deenergizing, allows the side switch to advance from first to second position. The movement of the side switch wiper 50 from first to second position transfers the battery connection from the vertical magnet 48 to the rotary magnet 49.

The calling subscriber now operates his calling device for the last digit 0, in response to which the connector line relay operates to transmit ten impulses through the rotary magnet 49 to battery B. The circuit of the relay 101 is opened upon the first deenergization of the relay 52. The relay 101, upon deenergizing, again closes a circuit through the private magnet 54 at the springs 97 and places a shunt around itself at the springs 89. The rotary magnet, responding to the ten impulses transmitted by the line relay 52, operates to rotate its wipers onto the contact of the desired line. The high speed impulses that follow cause the armature of the line relay 52 to vibrate very rapidly, thus causing the springs 55 and 56 to separate for an instant, which allows the relay 101 to again energize. The relay 101, upon energizing, opens the shunt around itself at the springs 89 and opens the circuit of the private magnet 54 at the springs 97. The private magnet 54, upon deenergizing, allows the side switch to advance one more position, *i. e.*, from second to third position. By the engagement of the side switch wiper 50 with its third-position contact point, a circuit is closed extending from ground G⁷ through the contact of springs 104 and 103, springs 93 and 94, springs 106, relay 107, lower winding of the relay 60 and the side switch wiper 50 (in third position) to battery B. The relay 60 does not receive sufficient current when connected in series with the relay 107 to operatively energize. The relay 107 upon energizing, extends the call through the wipers 45 and 46 to the called substation A'. A further result of the energization of the relay 107 is to close a circuit through the cut-off winding 111 of the line switch C' and to close a circuit through the ringing relay 112. The circuit for the cut-off winding 111 extends from ground G¹¹ through the contact of springs 109 and 110, private wiper 47, conductor 115 and the said cut-off winding 111 to battery B. The circuit for the ringing relay 112 extends from ground G¹¹ through the contact of springs 109 and 108, springs 116 and 119, ringing relay 112 and the interrupter 117 to battery B. The ringing relay, upon energizing, disconnects the calling line from

the called line and bridges the ringing current generator R across the called line to signal the called subscriber. The ringing relay is energized intermittently through the medium of the interrupter 117. Upon 70 the response of the called subscriber his line is provided with talking current through the windings of the back bridge relay 53, which relay, upon energizing, closes a circuit through the upper winding of the relay 60. This circuit extends from ground G¹² through the contact of springs 118, through the upper winding of said relay and the side switch wiper 50 (in third position) to battery B. The two winding of 80 the relay 60 assist each other and the said relay is operatively energized. The relay 60, upon energizing, opens the circuit of the ringing relay 112 at the springs 116 and 119 and closes a locking circuit for 85 itself through the springs 116 and 120 independent of the springs 118. A further result of the energization of the back-bridge relay 53 upon the response of the called subscriber is the transposition of the connections of the windings of the line relay 52 with regard to the line conductors 90 and 92, whereby the direction of current in the calling line is reversed. Conversation may now be carried on over the heavy 95 conductors shown.

After the conversation is completed, the connection is released by the hanging up of the receiver at the calling substation in the following manner: When the receiver at 100 the substation A is restored to the switch-hook, the separation of the hook-switch springs destroys the energizing circuit of the connector line relay 52. The line relay 52, upon deenergizing, closes a circuit through 105 the relay 99, which relay is slow to energize. The said circuit extends from ground G⁶ through the contact of springs 58, off-normal springs 121 and the said relay 99 to battery B. The relay 99, upon energizing, 110 closes a circuit through the release magnet 51 from ground G⁷ through the contact of springs 104 and 105 and the said release magnet 51 to battery B. The magnet, upon energizing, restores the switch shaft and 115 side switch wiper to normal position and its own circuit is broken by the deenergizing of the relay 99, which is caused by the separation of the off-normal springs 121 when the shaft reaches its lowest position. A further result due to the energization of the relay 99 is the opening of the circuit of the relay 87 at the springs 104 and 103. The relay 87, upon deenergizing, opens the holding circuit for the relay 86 of the selector E 120 and the holding winding 19 of the line switch C. The relay 86, upon deenergizing, closes a circuit through the release relay 40. This circuit extends from ground G⁴ through 125 the contact of springs 83, springs 84, off- 130

normal springs 38 and the release relay 40 to battery B. The relay 40, upon energizing closes a circuit from ground G³ through its normally open springs and the release magnet 37 to the battery lead 100. The selector E releases, breaking the circuit of its own release magnet when the shaft reaches its lowest position. The winding 19 of the line switch C, upon becoming deenergized, allows the plunger arm 15 to return to normal position.

It now having been explained how one subscriber establishes connection and releases the same, it will be explained how a connection is prevented from being made with a busy line and how the calling subscriber receives a busy signal when calling a busy number. If the number called is busy, there will be a guarding potential upon the connector private bank contact, just as explained in connection with the line switch C. The connector private wiper, upon engaging this guarding contact and at the instant the side switch passes to third position before the circuit of the private magnet 54 is broken, completes a circuit through the relay 60. This circuit extends from ground on the said private wiper 47 through the contact of springs 110 and 123, the lower winding of said relay 60 and the side switch wiper 50 to battery B. The relay 60, upon energizing, closes a locking circuit for itself extending from ground G⁷ through the contact of springs 104 and 103, springs 93 and 94, springs 124 and 120, upper winding of the relay 60 and through the side switch wiper 50 (in third position) to battery B. A further result due to the energization of the relay 60 is the giving of the busy signal to the calling subscriber. This circuit extends from the busy machine Q through the contact of springs 125, springs 127 and 126, over the conductor 92 to and through the substation A, return conductor 90 and the upper winding of the relay 52 to battery B. The calling subscriber, upon receiving the busy signal, hangs the receiver upon the hook, thereby releasing the connection in the manner above described.

It will thus be seen that I have devised a very efficient telephone system in which the automatic selector and connector switches are provided with motor magnets controlled by a series of impulses of one character, while the switching operations of said switch are controlled by impulses of a different character. Furthermore, these impulses are transmitted to the automatic switches over two sides of a metallic line circuit in series, the character of the operating impulses being in no way dependent upon the character of the switching impulses.

While I have illustrated my invention in connection with certain types of automatic switches, it will, of course, be understood that my invention is not limited to switches

of this type, but is equally as well adapted for use in connection with other systems which require separate and distinct operations over a single circuit.

What I claim as my invention is:— 70

1. In a telephone system, an automatic switch having a plurality of operating magnets, means for switching a connection from one to the other of said operating magnets, means including an impulse controller and 75 an impulse circuit over which current flows when closed for controlling said operating magnets by impulses of one character over said circuit, and for controlling said switching operation by impulses of a second character over said circuit, the resistance of the circuit when thus closed being the same in both operations.

2. In a telephone system, an automatic switch having a plurality of operative movements, and means for controlling the operation of said switch by a series of impulses of one frequency, followed by one or more rapid impulses. 85

3. In a telephone system, an automatic 90 switch having a plurality of operating elements, means for switching the connection from one to the other of said operating elements, means for controlling said operating elements by impulses of one frequency, and 95 means for controlling said switching operations by one or more rapid impulses.

4. In a telephone system, an automatic switch, a trunk line extending thereto, said switch including a line relay and a plurality 100 of operating magnets, means for operating said line relay by impulses of one character to control the operation of said switch, and means for operating said line relay by impulses of a different character to successively bring said operating magnets under 105 the control of said relay.

5. In a telephone system, an automatic switch, a trunk line extending thereto, a line relay, a pair of operating magnets, means 110 for transmitting a plurality of impulses through said line relay to control the operation of one of said operating magnets, and means for then transmitting one or more rapid impulses through said line relay to 115 bring said second operating magnet under the control of said line relay, said first means for then transmitting one or more impulses through said line relay to control the operation of said second magnet. 120

6. In a telephone system, an automatic switch including a plurality of operating magnets, a side switch for successively controlling the circuits of said magnets, means for controlling the operation of said magnets by impulses of one character, and means for controlling the operation of said side switch by one or more rapid impulses. 125

7. In a telephone system, a line circuit, an automatic switch having a plurality of 130

operating magnets, means for switching a connection from one to the other of said operating magnets, means including an impulse controller and an impulse circuit over 5 which current flows when closed for controlling said operating magnets by the impulses of one character over said circuit, and for controlling said switching operation by impulses of a second character over said circuit, said impulses being transmitted over two sides of said line circuit in series, the 10 resistance of the circuit when thus closed being the same in both operations.

8. In a telephone system, a line circuit, 15 an automatic switch having a plurality of operative movements, and means for controlling the operation of said switch by a series of impulses of one frequency, followed by one or more rapid impulses, said impulses 20 being transmitted over two sides of said line circuit in series.

9. In a telephone system, a line circuit, an automatic switch having a plurality of operating elements, means for switching the 25 connection from one to the other of said operating elements, means for controlling said operating elements by impulses of one frequency, and means for controlling said 30 switching operations by one or more rapid impulses, said impulses being transmitted over two sides of said line circuit in series.

10. In a telephone system, an automatic switch, a trunk line extending thereto, said switch including a line relay and a plurality 35 of operating magnets, means for operating said line relay by impulses of one character to control the operation of said switch, and means for operating said line relay by impulses of a different character to successively bring said operating magnets under 40 the control of said relay, said impulses being transmitted over a circuit including two sides of said trunk line in series.

11. In a telephone system, an automatic 45 switch, a trunk line extending thereto, a line relay, a pair of operating magnets, means for transmitting a plurality of impulses through said line relay to control the operation of one of said operating magnets, 50 means for then transmitting one or more rapid impulses through said line relay to bring said second operating magnet under the control of said line relay, and means for then transmitting one or more impulses 55 through said line relay to control the operation of said second magnet, said impulses being transmitted over a circuit including two sides of said trunk line in series.

12. In a telephone system, a line circuit, 60 an automatic switch including a plurality of operating magnets, a side switch for successively controlling the circuits of said magnets, means for controlling the operation of said magnets by impulses of one character, 65 and means for controlling the operation of

said side switch by one or more rapid impulses, said impulses being transmitted over two sides of said line circuit in series.

13. In a telephone system, a conductor and a source of current forming a circuit, a telephone for said circuit, an impulse sender for said circuit, a line, a telephone for said line, an automatic switch associated with said circuit, a relay and propelling magnets for said switch, means including said sender 70 for variably affecting the frequency of energizations of said relay for controlling said magnets to build up a talking circuit between said circuit and said line, and means for disconnecting said relay and for substituting another relay through which current for talking purposes is supplied to the said talking circuit.

14. In a telephone system, an automatic switch having a plurality of operating magnets means for switching a connection from one to the other of said operating magnets, means for controlling said operating magnet by impulses of one character, means for controlling said switching operation by impulses of a second character, and means for producing said impulses by breaking the 85 line circuit.

15. In a telephone exchange system, the combination with an automatic switch, 90 means for directing the action of said switch in response to current impulses of a certain frequency, of means for said switch responsive to current impulses of a different frequency for shifting the directive means, 95 substantially as set forth.

16. In a telephone system, a subscriber's line, a plurality of automatic switches, an impulse transmitter at the station on said line adapted to control the variable setting 100 of said switches by impulses produced in the line circuit and to cause the change over from one of said switches to the next by an impulse of shorter duration than the setting impulses.

17. In a telephone system, a subscriber's line, a plurality of automatic switches, an impulse sender at the substation on said line adapted to produce a uniform series of interruptions therein to control the variable 115 setting of said switches and to cause the change over from one switch to the next by a short interruption following each series.

18. In a telephone system, an automatic 120 switch having a plurality of operative movements, and means for controlling the operation of said switch by a series of impulses of uniform duration, followed by an impulse of shorter duration.

19. In a telephone system, an automatic switch having a plurality of operating elements, means for switching the connection from one to the other of said operating elements, means for controlling said operating 130

elements by impulses of a certain length, and means for controlling said switching means by an impulse of lesser length.

20. In a telephone system, an automatic switch having a plurality of operating elements, means for switching the connection from one to the other of said operating elements, means for controlling said operating elements by impulses of a certain length, 5 means for controlling said switching means by an impulse of a lesser length, and means for producing said impulses by breaking the line circuit.

21. In a telephone system, a subscriber's line, means for extending said line comprising an automatic switch, primary and secondary operating magnets in said switch, means for producing successive series of impulses of a particular duration in the line 15 circuit to cause the successive operation of said magnets, and means for causing the change over from one magnet to the other by an impulse of shorter duration than the operating impulses.

25. 22. In a telephone system, an automatic switch having primary and secondary operating magnets, a control relay and a circuit therefore, means for transmitting successive series of impulses over said circuit, whereby 30 said magnets may be successively operated under control of said relay, means for transmitting an impulse of shorter duration than the operating impulses, and means responsive to said short impulse for shifting the control of said relay from one magnet to the other.

23. In a telephone system, subscribers' lines, an automatic connector switch, means for operating said switch to connect with a 40 desired called line, test and switching relays in said connector adapted, respectively, to give the calling subscriber a busy signal and to complete connection to a called line, means for completing a circuit through said 45 relays in series after the connector has op-

erated, said test relay being normally unresponsive thereto, and a test wiper connected to the junction of said relays and co-operating with the test contact of the called line to cause the energization of one or the 50 other of said relays, depending on whether the called line is busy or idle.

24. In a telephone system, subscribers' lines, an automatic connector switch comprising talking conductors, means for operating said switch to connect said conductors with a desired called line, a switching relay in said connector controlling contacts in 55 said conductors, a test relay, a circuit completed when connection is established through said relays in series, said test relay being inoperative, a test wiper connected to the junction of said relays, test contacts for said lines, and a busy potential on the test contact of the called line if the same is in 60 use, whereby the said switching relay will be short circuited and the said test relay will be energized by way of said test wiper.

25. In a telephone system, subscribers' lines, an automatic connector switch, means for operating said switch to connect with a desired called line, test and switching relays in said connector adapted, respectively, to prevent and to complete connection to a 70 called line, an electro-magnet energized during the operation of said switch and deenergized thereafter to close a circuit through said relays in series, and a test wiper connected to the junction of said relays and co-operating with the test contact of the called 75 line to cause the energization of either the said test relay or the said switching relay, depending on whether the called line is busy or idle.

Signed by me at Chicago, Cook county, 85 Illinois, this 2nd day of April, 1914.

BERNARD D. WILLIS.
